UNITED STATES PATENT OFFICE.

CROMWELL O. CASE, OF NEW BRITAIN, CONNECTICUT, ASSIGNOR TO THE
P. & F. CORBIN, OF SAME PLACE.

DESIGN FOR A CASING FOR DOOR-CHECKS.

SPECIFICATION forming part of Design No. 29,042, dated July 12, 1898.

Application filed April 23, 1898. Serial No. 678,678. Term of patent 14 years.

To all whom it may concern:

Be it known that I, CROMWELL O. CASE, of New Britain, State of Connecticut, have invented a new and original Design for a Casing for Door-Checks, of which the following is a full, clear, and exact description, reference being had to the accompanying drawings, forming a part thereof.

In the drawings, Figure 1 is a view in perspective, and Fig. 2 is a plan view.

The leading feature of my design consists in a cylindrical body closed at each end and a smaller cylindrical body integral with said first-mentioned body and disposed at right angles thereto approximately midway the length of the larger cylindrical body, the smaller body being partially merged into the larger body.

A represents the larger cylindrical body, and B the smaller body. The body A is provided on one face with an extended flat portion and on one end with a notched projection 4 and on its other end with an integral annular projection 3. The smaller body is contracted at one end, as at 5, and provided with an annular projection 6 at its other end.

What I claim is—

The design for a casing for a door-check comprising a cylindrical body and a smaller cylindrical body at right angles to said first-mentioned body and partially merged therein as herein shown and described.

CROMWELL O. CASE.
